Primary Examiner — David G Muller*Assistant Examiner* — Christina Gabrielle Cosden(74) *Attorney, Agent, or Firm* — Carter, DeLuca & Farrell, LLP; George Likourezos(57) **CLAIM**

The ornamental design for a wrap-around gate latch, as shown and described.

DESCRIPTION

FIG. 1 is a perspective view showing my new design;

FIG. 2 is another perspective view thereof;

FIG. 3 is a front view thereof;

FIG. 4 is a rear view thereof;

FIG. 5 is left side view thereof;

FIG. 6 is a right-side view thereof;

FIG. 7 is a top view thereof;

FIG. 8 is a bottom view thereof; and,

FIG. 9 is a bottom perspective view of the claimed new design.

The portions of the wrap-around gate latch shown in broken lines form no part of the claimed design.
